UNITED STATES PATENT OFFICE.

EMILE RIMAILHO, OF PARIS, FRANCE.

REGULATING DEVICE FOR THE FLOW OF LIQUID IN ARTILLERY BRAKES.

Application filed February 3, 1922. Serial No. 533,948.

To all whom it may concern:

Be it known that I, EMILE RIMAILHO, a citizen of the Republic of France, and residing at Paris, No. 12 Rue de la Roche-5 foucauld, in the Republic of France, engineer, have invented certain new and useful Improved Regulating Devices for the Flow of Liquid in Artillery Brakes, of which the following is a specification.

10 This invention relates to a device employed in connection with an artillery brake of the hydraulic type provided with a valve for the discharge of the liquid which is submitted to the action of springs, the said 15 device controlling the regulation of the stroke of the valve and the tension of the springs and being applicable for use in cases where the main body of the brake is subject to recoil with the cannon, whilst the 20 piston rod is maintained in the fixed position.

The said arrangement, wherein the main body of the brake participates in the recoil action, possesses certain advantages as concerns ballistic operations, and is frequently employed in practice. According to this invention, the regulation is obtained in proportion to the angle given to the piece by means of an inclined plane submitted to the 30 action of a cylindrical cam having a suitable cross-section, whereupon a control arm provided with a roller is caused to slide during the recoil according to a generatrix, the said cam being revoluble by means of a 35 suitable device which enters into action when the piece is aimed in elevation. In these conditions, the said inclined plane will occupy for each aiming angle a determined position which it preserves throughout the 40 entire period of the recoil and which depends solely upon the orientation of the cam. The said cam is preferably set in rotation starting from a given aiming angle, and the position thereof will be subsequently 45 modified for all greater inclination which is given to the piece.

The following description, together with the accompanying drawing which is given by way of example, sets forth an embodiment of the invention, wherein:

Figs. 1 and 1^a are side elevations of the piece.

Fig. 2 is a vertical section on the line A—A, Fig. 1.

55 Fig. 3 is a partial vertical section on the line B—B, Fig. 1.

Fig. 4 is a horizontal section on the line C—C, Fig. 3.

1 indicates the piece, which is adapted to slide in the slides 2 mounted on a cradle in steel plate 3 which is secured to a cross-piece 4 carrying the trunnions 5. The said trunnions are pivoted to the cheeks 6 constituting the carriage proper. A brake body 7 is secured to the piece 1 for instance by a hoop 8, and the piston rod of the brake 9 is secured to the front part of the cradle 3. To the main body of the brake is secured a receptacle 10, containing in a known manner the valve employed for the discharge of the liquid which is subject to the tension of a weak spring, and also the stop-piece of the said valve which is separated from the said regulating inclined plane by a stronger elastic device. An arm 11 secured to the regulating inclined plane ends in a roller 12 which during the recoil movement is caused to roll upon a cam 13 of cylindrical form whose cross-section in the form of a spiral is shown in Fig. 3. The 80 said cam is mounted upon two trunnions 14 and 15 which are maintained in the bearings 16 and 17 secured to the cradle 3.

To the trunnion 14 is secured the bevel gear 18 co-operating with the gear wheel 19 mounted on the transverse shaft 20 which is revoluble in the wall of the cradle 3. On the shaft 20 is also mounted a spur gear 21 co-operating with a toothed quadrant 22 secured to the cheek 6. To prevent any flexion of the cam 13 it is maintained by the guide 23 secured to the main body of the brake 7. In order to provide for the rotation and the sliding movement of the said cam, according to the conditions depending upon the spiral form of the latter, the said cam is mounted in an external ring 24 which is revoluble in the guide 23. In these conditions, the said device is operated as follows: At the same time as the piece is aimed in elevation, the quadrant 22 controls the position of the cam 13 by means of the gear wheels 21, 19 and 18. By reason of the spiral form of the said cam, the roller 12 will be more or less raised according to the angle, and in consequence the inclined plane will come into action to a greater or less degree within the casing 10 in order to gradually counteract the lifting of the valve by the opposition of the resistance due to the powerful elastic device. It is preferable that the quadrant 22 should come into

110

- action only after a given value of the aiming angle is reached. To this effect, the said quadrant comprises a smooth portion 25 having a radius of greater value than that of the bottom of the teeth. In these conditions, during the entire passage of the smooth part of the said quadrant before the pinion 21, the latter will be immobilized and the device cannot be put out of order.
- 10 It is obvious that by suppressing the guide 23, the cam 13 may be given any suitable profile in order to obtain a constant reaction during the entire period of the recoil in a very exact manner. However, the arrangement as hereinbefore set forth will afford satisfactory results in practical operations.

Claims—

1. In an artillery brake of the hydraulic type, a regulating device for the flow of liquid comprising a regulating element for the flow, a revolute cam mounted on the cradle of the piece of artillery and acting upon the said regulating element, the said cam having the same length as the recoil stroke of the cannon, a piston fixed to said cradle, a hydraulic cylinder for the piston movable with the cannon, said cam being rotatable independently of said cylinder, and transmission means for effecting the orientation of the said cam in cooperation with the aiming of the cannon for elevation.
2. In an artillery brake of the hydraulic type, a regulating device for the flow of liquid comprising a regulating element for the flow, a roller disposed upon the said element, a revolute cam adapted to be mounted upon the carriage of the piece of artillery and having the same length as the recoil stroke of the cannon and a cross-section in the form of a spiral, the said roller being caused to roll during the recoil along a gen-

eratrix of the said cam, and transmission means for effecting the orientation of the said cam in cooperation with the aiming of the cannon for elevation.

3. In an artillery brake of the hydraulic type, a regulating device for the flow of liquid comprising a regulating element for the flow, a revolute cam mounted on the cradle of the piece of artillery and acting upon the said regulating element, the said cam having the same length as the recoil stroke of the cannon, a piston fixed to said cradle, a hydraulic cylinder for the piston movable with the cannon, said cam being rotatable independently of said cylinder, a bevel gear mounted on the axle of the said cam, a stationary toothed quadrant secured to the carriage of the piece of artillery, and gear wheels connecting the said quadrant with the said bevel gear.

4. In an artillery brake of the hydraulic type, a regulating device for the flow of liquid comprising a regulating element for the flow, a revolute cam adapted to be mounted on the cradle of the piece of artillery and acting upon the said regulating element, the said cam having the same length as the recoil stroke of the cannon, a bevel gear mounted on the axle of the said cam, a toothed quadrant secured to the carriage of the piece of artillery, and gear wheels connecting the said quadrant with the said bevel gear, the said quadrant having a non-toothed portion whereby the same shall be prevented from acting except after a stated value of the aiming angle is reached, the non-toothed portion having a greater radius than that of the bottom of the teeth.

In testimony that I claim the foregoing as my invention, I have signed my name.

EMILE RIMAILHO.
